TYPEWRITING MACHINE

Joseph P. Barkdoll, Groton, N. Y., assignor to
 L. C. Smith & Corona Typewriters, Inc.,
 Syracuse, N. Y., a corporation of New York

Application July 17, 1940, Serial No. 345,913

9 Claims. (Cl. 197—143)

The invention relates to improvements in typewriting machines, the improvements being particularly advantageous for use in small and low portable typewriting machines and relating to auxiliary paper supporting means for supporting work sheets as they are fed to and from the platen in typing.

It is a known practice in the art to provide typewriting machines with a pair of paper supporting fingers or arms associated with the paper table for extension from a compact position of non-use to a paper supporting position at the rear of the paper table to provide a more extended support than is afforded by the usual paper table for paper sheets as the latter are fed to and away from the platen, such fingers being particularly desirable in small compact portable typewriting machines.

The principal objects of the present invention are to provide a typewriting machine having an improved compactable and extensible set of such paper fingers or supports and are an improved mounting for the fingers.

Further objects of the invention are to provide an improved set of fingers connected and mounted in an improved and simple manner for extension and compaction of the set by direct movement by hand of either one of the paper fingers alone, and to provide such an auxiliary paper finger assembly which shall be very light and inexpensive.

To the foregoing and other ends which will appear from the following description of the preferred embodiment of the invention shown in the drawing, the invention consists in the features of construction, arrangements of parts, and combinations of devices and parts set out particularly in the appended claims.

In the drawing:

Fig. 1 is a fragmentary vertical longitudinal sectional view of the improved machine taken on the line 1—1 of Fig. 2, the paper fingers or arms being shown in extended or operative position;

Fig. 2 is a fragmentary top plan view of the machine;

Fig. 3 is a fragmentary rear view of the paper fingers and their mounting showing the paper fingers or arms in compacted or inoperative position, certain parts being broken away for greater clarity of illustration of features of the improvements;

Fig. 4 is a fragmentary plan view of the paper fingers and their mounting with the fingers positioned as shown in Fig. 3, the view being taken

looking downward perpendicularly to the upper side edges of the compacted fingers or arms;

Fig. 5 is a detail sectional view on the line 5—5 of Fig. 3;

Fig. 6 is a detail rear view of the fingers and their mounting showing the fingers in extended operative position, certain parts being broken away;

Fig. 7 is a detail sectional view on the line 7—7 of Fig. 6; and

Fig. 8 is a detail rear view of the paper fingers operatively positioned as shown in Figs. 1, 2 and 6.

The improvements are shown in a preferred form thereof incorporated in an otherwise known small, low-height, portable typewriting machine known as the Corona Zephyr. Only so much of the known machine as is necessary to a full understanding of the present improvements is shown in the drawing and will be described. Said known machine has a platen carriage 10 mounted to travel back and forth transversely of the machine upon a carriage bed 11 which is mounted on the main frame of the machine. The carriage has the usual roller platen 12 journaled thereon, and also has mounted thereon the usual paper table or apron 13 for guiding work sheets down under the platen from the rear for feeding of the sheets by the usual paper feed mechanism up in front of the platen past the printing or typing line of the machine. The carriage has detachably mounted thereon at the rear thereof a thin sheet metal decorative and machine-part-housing mask element 14. Said mask element has the usual integral bent arms 15 adjacent its ends clamped to the carriage by screws 16, said mask element also having the usual forwardly bent end portions provided with apertures through which protrude the usual mask-element-retaining studs 17 on the carriage.

The improvements constituting the present invention will now be described.

A bracket 19—19^a of thick and stiff sheet metal is rigidly held to mask element 14 midway the ends of said element and of the carriage 10. Said bracket supports the paper-supporting fingers or arms 18. The bracket comprises a main body portion 19 and a central stem portion 19^a bent at a considerable angle to the plane of the body portion. The body portion 19 is of flat bar-like form and is cut away along its lower edge from its two ends part way to the central stem portion to provide reduced end portions 19^b at opposite ends of the body portion. The mask element 14 is formed along its upper

edge behind the carriage and the paper table with a forwardly and downwardly rolled or bent upper edge portion 14^a extending transversely of the machine lengthwise of the carriage, which edge portion 14^a is formed with a longitudinal slot 20. Stem portion 19^a of the bracket 19-19^a extends down through this slot 20 with the lower edge of the wider medial part of body portion 19 of the bracket seated down on element 14 along the rolled edge portion 14^a of said element. Stem portion 19^a of the bracket is fixedly held to element 14 by a rivet 21, and the side edges of stem portion 19^a preferably abut the ends of slot 20, being formed with shoulders 19^c for abutting the slot ends. The body portion 19-19^b of the bracket lies preferably in an upwardly and rearwardly inclined plane, and is located slightly behind the rear upper end of paper table 13, as shown. The reduced end portions 19^b of the body portion of the bracket are spaced slightly above the rolled edge 14^a of mask element 14.

The front face of the body portion of the bracket is covered by a thin sheet metal decorative mask element 22 conforming to the shape of said body portion and having a rim 22^a covering the exposed edges of said body portion. The rim 22^a of element 22 is formed with lugs 22^b bent around behind the reduced end parts 19^b of the bracket to hold mask element 22 to the bracket.

The two paper-supporting arms or fingers 18 are flat bars of stiff and thick sheet metal and are pivotally supported on bracket 19-19^a-19^b at their inner ends by headed pivot studs 23. The studs are held at their forward ends rigidly and non-rotatably to said bracket and each arm 18 is pivoted close to its inner end on a different one of said studs, each stud having a head at its rear end between which head and bracket body portion 19 the arm is confined flatwise. The shanks of studs 23 are perpendicular to the inclined plane of bracket portions 19-19^b. Studs 23 are slightly spaced apart transversely of the machine along a horizontal line and slightly to opposite sides of the mid-length point of the carriage.

The paper-supporting arms or fingers 18 each has a rounded inner end edge concentric with its pivot, in which edge is cut an arcuate series of gear teeth 24. The teeth on the arms 18 form sector gears, one on each arm, which gears mesh with each other and permit swinging of the arms in unison through a limited arc of movement of each arm about its pivot, the gears being so arranged that the arms may swing from a compacted position of Figs. 3, 4 and 5 to an extended operative position of Figs. 1, 2, 6 and 8.

Fastened rigidly to each arm 18 and projecting rearwardly therefrom slightly outward from its pivot is a metal stud 25 which extends rearward further than the head of pivot stud 23 of the arm. A contractile coiled spring 26 has its opposite ends anchored to the outer ends of studs 25 and is adapted to move above and below the pivot studs during swinging of the arms 18 up and down to hold the arms in either extended or compacted position.

In their compacted position arms 18 extend substantially horizontally, and their compacting movement is limited by engagement of pointed edge lugs 18^a on the arms in apertures 27 in mask element 14. Spring 26 is preferably connected to the arms, as shown, so that it will move up past the common center line of the pair of pivot studs 23 after a very slight extending movement

of the arms 18 and will thereafter act to pull the arms to fully extended position and hold them there. The extending movement of the arms is arrested by edgewise engagement of the bars 18 above their pivots just before the gear sectors would otherwise demesh, as shown in Figs. 6 and 8. In extended position the arms 18 diverge in V formation from their pivots and lie in an upwardly and rearwardly inclined plane to support paper sheets passing between the table and the platen to the printing line of the machine and passing rearward over the platen from the printing line of the machine.

The arresting engagement of the lugs 18^a in holes 27 of mask element 14 prevents marring of the said decorative mask element. The constant pull of spring 26 on the rear ends of studs 25 slightly flares the arms 18 rearwardly from their pivots, as shown in Fig. 4, to cause said arms to clear lugs 22^b of bracket mask 22 and thus prevents scratching of exposable parts of the front faces of the arms 18 by the bracket and its mask.

It will be observed that a decorative and efficient auxiliary paper supporting means is thus provided for typewriting machines. It will also be observed that the pair of paper supporting arms may be shifted in unison by simply grasping and swinging one of said arms, the arms being geared together. It will also be observed that the spring functions not only to releasably hold the arms extended or compacted, but also functions to complete both a manually initiated compacting movement and a manually initiated extending movement of the fingers. It will also be observed that the lugs 18^a engage in holes 27 to interlock the arms 18 with mask member 14 near the free ends of the arms while the arms are in compacted position thus reducing liability of accidentally bending the arms 18 in using and handling the machine while the arms are compacted.

What I claim is:

1. In a typewriting machine having a roller platen, a traveling platen carriage in which said platen is journalled, and a carriage-carried paper-supporting table associated with said platen for directing paper beneath said platen from the rear toward the typing line of the machine, the combination of two auxiliary paper-supporting arms pivotally supported at one end of each arm to travel bodily with the carriage and to swing about parallel axes extending transversely of the platen from a compact inoperative position to an extended paper supporting position, said arms being formed with integral intermeshed gears at their pivoted ends for swinging of either arm by the other when the latter is swung about its pivotal axis, and the pivoted ends of said arms being located adjacent the receiving end of the paper table and approximately medi ally of the ends of the carriage, and a contractile coiled spring anchored at its opposite ends to the arms outwardly from the arm pivots and movable bodily across the pivotal axes of the arms during swinging of the arms to hold the arms in either the inoperative or paper supporting positions of said arms.

2. In a typewriting machine having a roller platen, a traveling platen carriage in which said platen is journalled, a carriage-carried paper-supporting table associated with said platen for directing paper beneath said platen from the rear toward the typing line of the machine, the combination of two auxiliary paper-supporting arms pivotally supported at one end of each arm to

travel bodily with the carriage and to swing about parallel axes extending transversely of the platen from a compact inoperative position to an extended paper supporting position, said arms being formed with integral intermeshed gears at their pivoted ends for swinging of either arm by the other when the latter is swung about its pivotal axis, and the pivoted ends of said arms being located adjacent the receiving end of the paper table and approximately medially of the ends of the carriage, a contractile coiled spring anchored at its opposite ends to the arms outwardly from the arm pivots and movable bodily across the pivotal axes of the arms during swinging of the arms to hold the arms in either the inoperative or paper supporting positions of said arms, and means on the carriage engageable by said arms to limit swinging of the arms away from each other with the arms held by said spring in their compact inoperative position with said arms extending substantially horizontally from their pivots toward opposite ends of the carriage, said arms being edgewisely engageable to arrest swinging of the arms toward each other with the arms held extended in their paper supporting position in V-formation by said spring.

3. In a typewriting machine having a platen carriage provided with a paper supporting table, a mask member held to the carriage at the rear of the carriage adjacent the receiving end of the paper table, a bracket held to said mask element medially of the ends of the carriage, a mask member covering the front of the bracket above said first mask member, two paper supporting arms each pivotally held adjacent one end thereof to said bracket at the rear of the bracket to swing outwardly toward the other arm from a compacted position in which the arm is swung against said mask member and extends toward one end of the carriage from its pivot, the pivotal axes of the arms being parallel and the pivoted ends of the arms being located approximately medially of the ends of the carriage, means connecting the arms to swing simultaneously toward and from compacted position, and a contractile coiled spring anchored at its opposite ends to the arms outwardly from the arm pivots and movable bodily across the pivotal axes of the arms to hold the arms in both compacted and extended position, portions of said arms being engageable adjacent the pivots of the arms to limit swinging of the arms from compacted position.

4. In a typewriting machine having a platen carriage provided with a paper-supporting table, a pair of inter-gearied paper-supporting arms pivotally supported by the carriage for simultaneous swinging thereof about parallel axes between a compact inoperative position of said arms and an extended operative paper supporting position in which said arms extend beyond the receiving end of the table to provide a more extended support for paper, and a contractile coil spring anchored at its ends to the arms outwardly from the arm pivots and movable bodily across the pivotal axes of the arms to yieldingly hold the arms extended and compacted relatively to the paper table.

5. A typewriting machine as claimed in claim 3, wherein each arm has a tapered projection, and the mask element has two apertures in which said projections are partly engageable to limit compacting swinging movements of the arms and interlock the arms with said mask element.

6. A typewriting machine as claimed in claim 1, having means on the carriage for limiting the swinging compacting movement of the arms, said means and said arms having provisions for interlocking the arms with said means while the arms are compacted.

7. In a typewriting machine having a roller platen, a traveling platen carriage in which said platen is journalled, and a carriage-carried paper-supporting table associated with said platen for directing paper beneath said platen from the rear toward the typing line of the machine, the combination of two auxiliary paper-supporting arms pivotally supported at one end of each arm to travel bodily with the carriage and to swing about parallel axes extending transversely of the platen from a compact inoperative position to an extended paper supporting position, means connecting together the pivoted ends of said arms for swinging of either arm by the other when the latter is swung about its pivotal axis, and the pivoted ends of said arms being located adjacent the receiving end of the paper table and approximately medially of the ends of the carriage, and a contractile coiled spring anchored at its opposite ends to the arms outwardly from the arm pivots and movable bodily across the pivotal axes of the arms during swinging of the arms to hold the arms in either the inoperative or paper supporting positions of said arms.

8. In a typewriting machine having a platen carriage provided with a paper supporting table, a bracket mounted on the carriage adjacent the receiving end of the table, said bracket comprising a long flat bar-like main body portion and a central depending stem portion mounted on the carriage medially the ends of the carriage, the body portion forming two horizontal arms extending transversely of the carriage from the central stem, two paper supporting arms each pivotally held adjacent one end thereof to said bracket at the rear of the bracket to swing outwardly and upwardly toward the other arm from a lower compacted position in which the arm is swung against the rear face of said bracket and extends along the bracket toward one end of the carriage from its pivot and beyond the adjacent end of the bracket, the pivotal axes of the arms being parallel and the pivoted ends of the arms being located approximately medially of the ends of the carriage, means connecting the arms to swing simultaneously toward and from compacted position, and a contractile coiled spring anchored at its opposite ends to the arms outwardly from the arm pivots to hold the arms in extended position.

9. In a typewriting machine having a platen carriage provided with a paper-supporting table, a pair of inter-gearied paper-supporting arms pivotally supported by the carriage for simultaneous swinging thereof about parallel axes between a compact inoperative position of said arms and an extended operative paper supporting position in which said arms extend beyond the receiving end of the table to provide a more extended support for paper, and a contractile coil spring anchored at its ends to the arms outwardly from the arm pivots to yieldingly hold the arms extended to operative position.
